NURSER

Cyril R. Porhouse, Kent, and William B. McIntosh, Akron, Ohio, assignors to The Pyramid Rubber Company, Ravenna, Ohio, a corporation of Ohio

Filed May 31, 1957, Ser. No. 662,795

3 Claims. (Cl. 215—11)

This invention pertains to nursing bottles, better termed nursing units or simply nursers, i.e., a bottle or other container for liquid having a nipple at the mouth of the bottle through which the liquid can be withdrawn. The invention pertains particularly to nursers having some means for admitting air to the nusser as liquid is withdrawn, thereby preventing a vacuum from building up inside.

This application is a continuation in part of our prior copending application S.N. 453,292, filed August 31, 1954, entitled "Nusser," which was a continuation-in-part of our application S.N. 441,784, filed July 7, 1954, now abandoned, which was co-pending therewith, entitled "Nusser."

A vacuum makes it difficult to suck liquid from a nusser and ultimately causes the nipple to collapse completely, preventing further withdrawal of liquid. When an infant cannot easily suck liquid from the nusser it begins to swallow air which causes stomach distress known as colic.

On the other hand, if a nusser is too freely vented the liquid will flow out of the nipple by gravity without any sucking by the infant. Filling the infant's mouth with liquid when it is not prepared to receive it may cause the liquid to run down the windpipe instead of into the stomach, thereby preventing normal respiration and also irritating the lining of the windpipe, this type of distress being known as choking or gagging.

A nusser which is vented sufficiently to prevent substantial vacuum buildup but not so much as to allow substantial gravity feed may be said to be properly vented. However, the degree of venting corresponding to proper venting may occupy a certain range within which changes in the size of the vent opening will serve to regulate the rate of flow from the nusser.

It is an object of the invention to provide a nusser having venting means which can be adjusted to bring the venting within the proper range.

It is a further object of the invention to provide a nusser having venting means which can be adjusted within the range of proper venting to regulate the rate of liquid flow from the nusser.

It is another object of the invention to provide a nusser which will not leak liquid through the venting means.

A further object of the invention is to provide better means for securing the nipple to the mouth of the liquid container.

Other objects and advantages of the invention will appear from the following description of preferred embodiments thereof in which:

Figure 1 is a vertical section through a nusser embodying the invention;

Figure 1A is a front elevation of the nipple shown in Figure 1;

Figure 2 is a bottom view of the screw cap forming part of the nusser shown in Figure 1;

Figures 3 and 4 are vertical sections through a nusser embodying the invention showing a modified form

2

thereof, the sections being taken on lines 3—3 and 4—4 of Figure 5;

Figure 5 is a top view of a bottle used in the nusser of the Figures 3 and 4 embodiment of the invention, and 5 also for comparison showing at 1—1 the plane of the Figure 1 section;

Figure 6 is a horizontal section through the top of the nusser of the Figures 3 and 4 embodiment taken on line 6—6 of Figure 7; and

10 Figure 7 is a vertical section on the line 7—7 of Figure 6.

Figure 8 is a plan view of a seal disc suitable for use with either embodiment of the invention;

Figure 9 is a quarter section showing the nusser of 15 Figure 1 with the nipple inverted and the seal disc in place to seal the nusser for storage or travel; and

Figures 10A, 10B, and 11 are fragmentary vertical sections showing further modified forms of the invention.

Referring now to Figure 1 there is shown a nusser 20 comprising a glass bottle or other liquid container 11, only the upper portion of which is shown. The bottle is provided with a decorative bead 12 around its neck and a screw thread 13 near its mouth. The lip 14 is rabbed at 15 around its outer periphery.

25 Over the mouth of the bottle is disposed a rubber nipple 21, also shown separately in Figure 1A. The nipple has a tubular discharge tip 22, the upper end of which is closed except for one or more small discharge openings (see Figure 3). The lower end of the tip merges with a hollow hemispherical body portion 23. There is an annular shoulder 24 around the lower part of the body portion 23. Three or more radial lugs such as that shown at 25 depend from the underside of shoulder 24. The lower end of the body portion 23 merges with 30 a cylindrical conduit portion 26. Three or more vertical ribs such as that shown at 26A project radially from conduit 26, preferably being disposed under lugs 25. At the lower end of the conduit portion is an exterior radial flange 27 which rests on lip 14 of the bottle. The junction of the flange 27 with conduit portion 26 is of reduced thickness, as shown at 28, in order to permit easy flexure. A plurality of holes, such as 29, 30, extend through the nipple flange, the outer edges of the holes being tangent to the inner edge of the bottle lip.

35 A Bakelite cap 40, also shown separately in Figure 2, holds nipple 21 on bottle 11. The cap has a flat circular disc shaped top portion 41 through the center of which is a hole 42 of slightly larger diameter than the outer diameter of the conduit portion 26, of the nipple, leaving an annular passage 39 therebetween, but of smaller diameter than the outer diameter of shoulder 24. The thickness of the top portion of the cap is equal to the distance between the top of flange 27 and the bottoms of lugs 26. On the lower face of the top portion 41 is a 40 circular bead or axially extending circular flange 43. Depending from the outer edge of top portion 41 is a cylindrical skirt 44 which has an internal screw thread 45 which meshes with thread 13 at the bottle mouth. Around the outside of the skirt are disposed three groups of three vertical flutes 51—59 (see also Figure 7).

45 The inner idiameter of the skirt 44 is substantially equal to the outer diameter of nipple flange 27, and radius of hole 42 is substantially equal to the radial distance from the nipple axis to the extremity of ribs 26A, whereby the nipple 21 is positively centered in cap 40 and hence on bottle 11.

50 In assembling the nusser the nipple tip and body are pushed through the hole in the cap, the nipple collapsing enough to allow shoulder 24 to pass through the hole 70 and then expanding again so that shoulder 24 overlaps the inner periphery of the cap, locking the cap between the nipple flange and the lugs under the shoulder on the

nipple. The cap is then screwed on to the bottle, thereby holding the nipple over the bottle mouth. The bead 43 presses into the top of the flange and the lip presses into the underside of the flange, thereby locking the nipple in place against radial inward strains created by tugging on the nipple during feeding.

In operation, as liquid is withdrawn from the nurser through the tip of the nipple, the lowered pressure in the nurser causes the nipple flange to flex inwardly under atmospheric pressure, thereby creating an air passage between the top of the flange and underface of the cap leading to the holes 29, 30. Air then enters the nurser to equalize the pressure between the inside thereof and the atmosphere, thereby preventing nipple collapse and making it easier to withdraw more liquid from the nurser.

The path of the air entering the nurser is indicated by the arrows in Figure 1. The air enters over the top portion 41 of cap 40, passing under shoulder 24 between lugs 25. The air then passes through passage 39 between the hole 42 in the top of the cap and the conduit portion 26 of the nipple and thence under the cap over the nipple flange to holes 29, 30 and into the interior of the nurser.

When the pressure inside the nurser has risen to nearly the same as that outside the nurser, the nipple flange resumes its original position with the top of its flange in engagement with the underside of the top of the cap, thereby covering over the holes 29, 30 and closing the passage between cap and flange leading to the holes 29, 30 from annular passage 39.

The exact position of the holes 29, 30, adjacent the inner edge of the bottle lip is important. If the holes were moved outwardly over the bottle lip, they would be partially or entirely blocked by the bottle. If the holes were spaced inwardly from the bottle lip, they might not always be tightly blocked by the top of the cap when the pressures were equalized, thereby allowing liquid to leak out of the nurser when turned on its side or upside down as is usual during use. By placing the holes next to the inner edge of the bottle where the flange of the nipple is clamped between the cap and bottle, there is a strong force tending to hold the portion of the nipple flange around the holes tight against the underside of the cap. This is due partly to the thick section of the nipple flange and partly to the rigid support provided by the cap and bottle immediately adjacent to the holes which tends to keep the flange parallel to and in contact with the underside of the cap. Farther toward the center of the nipple, there is a tendency for the nipple to sag, particularly as the thin section 28 is approached. By making the nipple flange flexible, especially near the center, and placing the holes as far from the center as possible, a very efficient check valve is provided which not only admits air automatically to eliminate any pressure differential between the interior and exterior of the bottle but also closes tightly to prevent any leakage of liquid from the nurser.

A most important advantage of placing the holes in the nipple adjacent the inner edge of the bottle lip lies in the fact that when so placed the size of the holes can be adjusted by screwing the cap up tighter or less tight on the bottle. Since rubber, like water, is substantially incompressible at ordinary pressures, it flows when subjected to unequal pressure, and hence flows inwardly to close up the holes 29, 30 when the cap is screwed on tight. The size of the openings can thus be adjusted according to the degree of tightness of the screw cap which varies the flow of the rubber into the holes. By this means the size of the vent openings can be adjusted to bring the degree of venting within the proper range to prevent vacuum buildup but not allow gravity discharge. In addition, the size of the openings can be reduced or enlarged within the range of proper venting to regulate the rate of feeding, since small openings will not vent

the nurser fast enough to allow as fast discharge as will larger openings. The range of regulation will lie within the total range of adjustment and cover only that portion of the total range of adjustment corresponding to sufficient but not excessive venting.

Referring now to Figures 3 and 7, there is shown a nurser generally similar to that shown in Figures 1 and 2. Corresponding parts have been given the same number except that those in Figures 3-7 have 100 added thereto. The screw cap 140 is identical with cap 40 of Figures 1 and 2. The nipple 121 is the same as nipple 21 except that thin section 28 and holes 29 and 30 are eliminated. Also, the lugs 25 and ribs 26A may be omitted and the conduit 26 enlarged to fit more closely inside hole 42 and shoulder 24 lowered to fit more closely on top of the top portion 41 of cap 40, as shown. The bottle 111 is the same as bottle 11 except for the addition of a plurality of radial lugs such as the three lugs 161, 162, 163 extending across the lip of the nipple.

As shown best in Figures 3 and 5, lug 163 is disposed near the upper and lower ends 164, 165 of the thread 113 at the mouth of the bottle. The thread 113 is the same as thread 13 of bottle 11, and is depressed at 166, 167 over the vertical parting line between the two halves of the molded glass bottle. As shown in Figure 5, the two lugs 161, 162 are each spaced 120 degrees azimuthally around the vertical axis of the bottle from lug 163. The lugs 161, 162 thus lie near to the thread depressions 166, 167.

When the screw cap 140 is tightened on bottle 111, the nipple flange 127 is pressed down tight on bottle lip 114 (see Figure 4) and the rubber of the nipple flange flows to fit closely around the lugs 161, 162, 163. Unless the cap is screwed on very tight, however, passages will be left under the nipple flange and over the bottle lip on each side of each lug. See for example passages 168, 169 adjacent lug 163 in Figure 3 and 7, shown greatly exaggerated in size for clarity.

The assembly of the nurser of Figures 3-7 is the same as that of the nurser of Figures 1 and 2. The operation is similar. However, in the embodiment of Figures 3-7 the passages for air flow are never closed when the nurser is in use, the natural resistance to liquid flow of capillary passages such as 168, 169 being relied upon to prevent leakage of liquid from the nurser.

The air intakes paths of the Figures 3-7 are best shown in Figures 3 and 7. The air enters under the lower edge of skirt 154 and passes between the bottle and cap at each of the thread depressions 166, 167 to the nearby passages over the bottle lip adjacent lugs 162, 163, and passes between the bottle and cap between the thread ends 164, 165, to the nearby passages 168, 169 over the bottle lip adjacent lugs 163.

As best shown in Figures 6 and 7, the bead 143 cooperates with the lugs 161, 162, 163, by concentrating the pressure and causing the rubber to flow in closer against the lug than at points not under the bead. Bead 143 thus has a dual function in the embodiment of Figures 3-7. As in the Figures 1 and 2 embodiment, the size of the vent openings is adjusted by varying the tightness of the screw cap. In this way the size of the openings can be adjusted until brought with the range of proper venting under widely varying circumstances, and thereafter the flow of the nurser, can be regulated within such range by minor adjustments of the tightness of the screw cap.

Referring now to Figure 8, there is shown a Bakelite seal disc 200 comprising a flat outer rim 201, a circular central depressed area 202A, 202B, an upstanding semi-circular flange 203, and an upstanding annular flange or bead 204.

Figure 9 shows how the nurser is arranged for storage and travel, the nipple 21 being inverted and the seal disc being disposed over the nipple and the cap 40 screwed in place over them with the flange 204 extending through

hole 42 to centralize the disc over the nipple. The depressed area of the disc seals against the conduit portion 26 of the nipple to prevent liquid leaking through the discharge holes such as 70 in the tip of the nipple from escaping, and the rim 201 sealing over the vent holes such as 29 to prevent leakage therethrough. Since the central area of the disc is depressed slightly below the rim 201, it causes the nipple to be pushed down into the bottle slightly so that the elasticity of the nurser pushes it tight against the disc to form a tight seal.

The nurser of the Figures 3-7 embodiment is also sealed for travel and storage by means of the seal disc shown in Figure 8, the disposition of the disc relative to the nipple being the same as that shown in Figure 9. By screwing the cap on very tight the vent passages adjacent lugs 161, 162 can be completely closed.

When it is desired to use the nurser after storage, the cap is unscrewed and the nipple and disc are picked up together between thumb and forefinger placed at diametrically opposite sides of the peripheries thereof. The nipple tip is then placed in the hole in the cap and the body and shoulder of the nipple are pushed through using the seal disc as a pushing tool. The seal disc is easily held by the flange 203 between thumb and forefinger. After the nipple has been locked in place in the cap, the cap is screwed onto the bottle and the disc laid aside for future use. By this method of assembly the nipple tip and body need not be touched with the hand.

It is to be noted that in both embodiments of the invention there is provided a nurser which has venting means that can be adjusted to the proper range and by minor adjustments within that range the flow can be regulated. To the achievement of this fine control the vertical ribs 151-159 forming a good hand grip make an important contribution.

The nipple shown in the Figures 1 and 9 embodiment may be used with the bottle of the Figures 3-7 embodiment, the cap shown in Figure 2 and the disc shown in Figure 8 being the same in both embodiments. By combining the nipple shown in Figures 1 and 9 with the bottle shown in Figures 3-7, a dual venting system is provided which permits a wider range of adjustment. Such an arrangement is shown in Figure 10B. Also, in such a dual venting construction, the holes in the nipple could be moved inwardly away from the bottle lip, as shown in Figure 10A, so as to be unaffected by the compression of the nipple flange by the screw cap. In such case the holes through the nipple flange would provide a constant amount of venting which would be made small enough so that a certain amount of additional venting over the bottle lip would be desirable and regulation would be accomplished by varying the size of the vent passages over the bottle lip. A dual venting system makes possible the use of lower ribs across the bottle lip since a part of the venting is through the holes in the nipple flange. This decreases any tendency for leakage over the bottle lip and enhances capability of smooth regulation.

Figure 11 shows a modification of the Figure 1 embodiment in which the single annular bead 43 on the underside of the screw cap is moved inwardly adjacent the inner edge of the bottle lip to the position shown at 43A whereby the bead serves not only to retain the nipple better but also assists in varying the size of hole 29 enhancing regulation of the nurser. If desired, an additional annular bead 43B may be provided nearer the outer periphery of the bottle lip where it can more easily force the outer edge of the nipple down into rabbet 15. For clarity in showing the rabbet 15 the rubber of the nipple flange is not shown as pushed down into the rabbet in any of the drawings although obviously it is actually so displaced. It may also be mentioned in connection with the drawings that the outer edge of the nipple flange will preferably actually be in contact with the inner periphery of the skirt of the screw cap whose internal diameter at this point is equal to the internal

diameter of the crest of its screw thread. Thus the edge of the nipple flange is closely supported on all sides so that compression of the flange will more positively cause flow of the rubber radially inwardly and vary the size of the vent hole 29.

The Figure 11 dual bead cap can be used also with the bottle and nipple shown in Figure 3 or Figure 10A or Figure 10B as well as with the bottle and nipple of Figure 1 as shown in Figure 11.

10 While preferred embodiments of the invention have been shown and described, many modifications thereof can be made by one skilled in the art without departing from the spirit of the invention and it is desired to protect by Letters Patent all forms of the invention falling within 15 the scope of the following claims.

We claim:

1. In a nurser comprising a bottle having a screw thread around its neck, a rubber nipple having an annular flange extending radially therefrom, the outer portion of said flange extending over and being supported by the lip of the bottle, and a cap having an apertured disc portion fitting over the nipple flange clamping said outer portion of the nipple flange to said bottle lip and having a depending annular skirt portion internally threaded to engage the bottle thread, the inner diameter of said flange being smaller than the inner diameter of said lip, leaving an inner portion of said flange unsupported by said bottle lip, said nipple flange having a vent hole of uniform cross-section extending transversely through said unsupported portion thereof, said disc portion of said cap normally engaging said inner portion of the nipple flange inwardly from said vent hole, the portion of the lip-facing surface of said flange immediately adjacent said vent hole being flat and the terminus of said vent hole at said surface being coplanar with the undersurface of said outer portion of said flange that is supported by the lip of the bottle, said inner portion of the nipple flange having an annular portion of reduced thickness located inwardly from said vent hole providing flexibility to the nipple flange, whereby there is provided a valve action in that on creation of a partial vacuum in the bottle said inner portion of the nipple flange flexes away from the disc portion of the cap covering the top of said vent hole to relieve the vacuum following which said inner portion of the flange returns to engagement with the underside of the cap to close the top of the vent hole against leakage of liquid from the nurser; the improvement according to which said vent hole through the inner portion of the nipple flange is located at the juncture of said outer portion and said inner portion of said nipple flange immediately adjacent and tangent to the inner edge of the bottle lip; and there is provided a rabbet around the outer periphery of the bottle lip cooperating with annular retaining means between the underside of the screw cap and the top of the nipple flange overlying the bottle lip to maintain precisely said location of said vent hole despite tension on said nipple during use, said rabbet receiving rubber flowing from said outer portion of said nipple flange in response to engagement of said annular retaining means between said cap and nipple flange; said cap, bottle lip, and inner portion of said nipple flange then confining said outer portion of said nipple flange in that the under surface of said disc portion of the cap fully and directly engages the top of said outer portion of the nipple flange, and the top of the bottle lip fully and directly engages the bottom of said outer portion of nipple flange, and the inner diameter of the upper portion of the skirt is as small as the inner diameter of the crest of the thread inside the skirt, and the outer diameter of the nipple flange directly and fully engages the inside of said upper portion of the skirt, the fact that the outer diameter of the nipple flange equals the inner diameter of the uppermost portion of the skirt also serving to position said vent hole precisely initially; and in addition to said annular retaining means there is provided between the underside of the screw cap and the

7 top of the nipple flange overlying the bottle lip an annular bead under the disc portion of the cap located inwardly from said annular retaining means but overlying said bottle lip and deforming the upper surface of said outer portion of the nipple flange by pressure thereagainst when said cap is screwed on to cause the confined rubber of said outer portion of the nipple flange to flow into said vent hole to a degree varying with the tightness of the screw cap, whereby the size of said vent hole can be varied by adjusting the tightness of the screw cap while still maintaining said valve action to prevent leakage of liquid out of the nurser through said vent hole.

2. The combination of claim 1 in which said annular retaining means is a second annular bead on the underside of said disc overlying the outer edge of that part of the nipple flange in contact with the lip of the bottle and in which the said first bead on the underside of the disc overlies that part of the nipple flange in contact with the bottle lip that is adjacent said vent hole.

3. The combination of claim 1 in which there is a radial lug across the lip of the bottle integral therewith and

5 forming additional vent passages at either side of said lug beneath said flange, and in which the thread on the bottle is depressed at diametrically opposite points along the parting line of the bottle to provide vent passages leading to the bottle lip.
